CLAIM

The ornamental design for an electrical connector, as shown and described.

DESCRIPTION

FIG. 1 is a first perspective view of an electrical connector; FIG. 2 is a second perspective view of the electrical connector; FIG. 3 is a perspective view of the electrical connector with the plug and receptacle connected; FIG. 4 is a perspective view of a plug of the electrical connector; FIG. 5 is a front view of the plug; FIG. 6 is a rear view of the plug; FIG. 7 is a left view of the plug; FIG. 8 is a right view of the plug; FIG. 9 is a top view of the plug; FIG. 10 is a bottom view of the plug; FIG. 11 is a perspective view of a receptacle of the electrical connector; FIG. 12 is a front view of the receptacle; FIG. 13 is a rear view of the receptacle; FIG. 14 is a left view of the receptacle; FIG. 15 is a right view of the receptacle; FIG. 16 is a top view of the receptacle; and, FIG. 17 is a bottom view of the receptacle.
